UNITED STATES PATENT OFFICE.

JOHN E. DUSANG, OF LARUE, OHIO.

FENCE-POST.

1,198,117.

Specification of Letters Patent. Patented Sept. 12, 1916.

Application filed April 9, 1915. Serial No. 20,229.

To all whom it may concern:

Be it known that I, JOHN E. DUSANG, a citizen of the United States, residing at Larue, in the county of Marion and State 5 of Ohio, have invented a new and useful Fence-Post, of which the following is a specification.

This invention relates to metal fence posts, one of its objects being to provide a post 10 formed of sheet metal bent to such shape as to provide a post which is reinforced against transverse strains.

A further object is to provide a novel 15 form of anchoring means for preventing the post from pulling out of the ground, said anchoring means being also formed of sheet metal and being applied readily to the post.

A further object is to provide improved 20 means for fastening wires to the post.

With the foregoing and other objects in view which will appear as the description 25 proceeds, the invention resides in the combination and arrangement of parts and in the details of construction hereinafter described and claimed, it being understood that changes in the precise embodiment of the invention herein disclosed, can be made within 30 the scope of what is claimed, without departing from the spirit of the invention.

In the accompanying drawings the preferred form of the invention has been shown.

In said drawings:—Figure 1 is a front elevation of a post embodying the present 35 improvements. Fig. 2 is a vertical longitudinal section therethrough. Fig. 3 is a section on line A—B Fig. 2. Fig. 4 is a perspective view of the anchor detached.

Referring to the figures by characters of reference 1 designates a post formed of 40 sheet metal and which is triangular in cross sectional contour, the blank of which the post is made being folded longitudinally to form the front ridge 2 and a rear reinforcing rib 3 extending throughout the length 45 of the post, said rib being produced by flattening one corner portion of the post. The two longitudinal edges of the blank are fastened together by rivets 4 or in any other suitable manner and likewise serve to rein-

force the post longitudinally, as will be apparent by referring to Fig. 3. In the ridge 2 are provided spaced openings 5 adapted to receive the longitudinal wires of the fence fabric, these wires being held to the post by a rod 6 insertible longitudinally within the 50 post and between the inner face of the ridge 2 and the wires. In the drawings the wires have been indicated at W.

The back wall of the post 1 is provided with an integral hook 7 adapted to engage 60 the lower edge of a cross strip 8 from the upper edge of which extend forwardly projecting wings 9 adapted to lie close to but beyond the sides of the post. Secured to the strip 8 is an angle strip 10 having ears 11 65 riveted or otherwise attached to the strip 8, the angle strip 10 and strip 8 defining a space designed to receive the lower portion of the post 1. The two strips 8 and 10 cooperate to form an anchor and this anchor may be reinforced by a metal strap 12 fitting about 70 the post 1, and riveted or otherwise secured to the anchor. When the anchor is applied to the post it is slipped over the end of the post and brought with the lower edge of 75 the strip 8 in engagement with the hook 7, as shown in Fig. 2. By then embedding the anchor in the ground, it will be apparent that the post will be held against accidental withdrawal from the ground.

It will be seen that the device herein described can be cheaply manufactured and readily set up for use. Furthermore, the wires of a fence can be easily attached to or disconnected from the post and by having 85 the openings 5 regularly spaced, fence fabrics of different mesh can be attached to the post without requiring posts of special construction.

What is claimed is:—

A sheet metal anchor including a flat strip, spaced wings extending laterally from the top edge of the strip, a second strip secured to the first named strip and having an angular offset portion below the space between the flanges, the two strips defining a triangular post receiving space, a triangular post fitted snugly within said space,

said post being formed of sheet metal, and
a hook extending throughout the width
of one wall of the post and formed by the
lower end portion of said wall, said hook en-
gaging one of the strips of the anchor to
limit the upward movement of the post
through the anchor.

In testimony that I claim the foregoing
as my own, I have hereto affixed my signa-
ture in the presence of two witnesses.

JOHN E. DUSANG.
